HAND STAMPS

Charles B. Huppert, 1336 W. Birchwood Ave.,
Chicago, Ill.

Filed Aug. 8, 1958, Ser. No. 754,075

5 Claims. (Cl. 101—103)

This invention relates to improvements in hand stamps. One of the objects of this invention is to provide a hand stamp with an independent printing unit which is detachably secured to the supporting frame to permit ready attachment and detachment of the printing unit.

Another object of this invention is to provide a hand stamp, including self-inking hand stamps and numbering machines in which the printing unit is detachably secured to the holder.

Present day hand stamps, particularly self-inking hand stamps are provided with printing units which are either permanently secured to the main supporting frame and form an integral part of the hand stamp or can only be detached by practically dismantling the unit. Thus, for every different size and style of printing type desired either the entire assembly must be substantially dismantled or a complete separate printing unit is required. Moreover, in self-inking hand stamps the printing unit must constantly be replaced due to hard usage which makes it necessary for new printing units to be installed. This is all eliminated by this invention, as there is provided a holder which will detachably support any one of a plurality of different types of printing units. The printing units are readily attachable to the holder when desired and detachable therefrom for replacement or substitution by another printing unit. Thus, with one holder an infinite number of printing units may be used as desired, thereby reducing the cost of the same, as well as reducing the necessary storage space therefor.

Other objects will become apparent as this description progresses.

In the drawings:

Fig. 1 is a front elevational view partly in section of the hand stamp embodying this invention.

Fig. 2 is an enlarged view partly in cross-section taken on lines 2—2 of Fig. 1.

Fig. 3 is an exploded view showing the position of the printing unit prior to attachment to its depressible supporting frame, and

Fig. 4 is an enlarged view partly in cross-section taken on lines 4—4 of Fig. 1.

The unit includes a main base frame generally indicated at 10, having a pair of narrow side members 12 connected by a top cross-member 14 to which is secured a sleeve 16. The side members 12 of the main frame have a widened portion 18 which extends to the bottom of the side members 12 and secured to the bottom of the side members 12 is a bottom plate 20 having a central rectangular opening 22 through which the printing head descends for printing, as is well understood.

The plate 20 is provided with a plurality of spaced apertures on each side of the central opening and a pair of rubber gaskets 24 are secured thereto by engagement of the pins 25 on the gaskets with said openings.

Supported on said main base frame 10 is a depressible sub-frame generally indicated at 26, of inverted U shape, having a pair of spaced side members 28 and a top con-

2

necting transverse member 30. Secured to the top of the transverse member 30 is a tubular stem 32 which extends upwardly through the sleeve 16 and has a knob or handle 34 affixed to the top thereof. Supported inside the tubular stem 32 is a coil spring 36, the bottom of which rests on a manually slideable cross-pin 38 secured to the sleeve 16 and the top of the spring rests against the inside of the top of the stem 32 to normally urge the tubular stem 32 and depressible sub-frame 26 upwardly to the position shown in Fig. 1, to maintain the printing unit in non-printing position. The tubular stem 32 is provided with opposed vertical slots 33 which ride in the pin 38. One of the vertical slots 33 has a pair of spaced enlarged recesses 33a and 33b which are adapted to be engaged by the enlarged portion of the slideable pin 38 to lock the depressible stem 32 and sub-frame 26 in either of two depressed positions. The foregoing structure and function is conventional in the art.

Each of the side members 28 of the depressible sub-frame has an outwardly extending pin 40 which rides in the vertical guide slots 42 in the sides 12 of the main frame 10. This is conventional in the art.

Pivottally secured as by a pin 44 to each of the sides 28 of the depressible frame 26 is a link 46, the opposite end of each link being pivotally secured as at 48 to the ink pad carrier generally indicated at 50. The ink pad carrier 50 has at each of its opposite sides an upward extension 52 whereby it is pivotally secured as at 54 to the widened sides 18 of the side members 12 of main frame 10. The ink pad 56 is supported in a metal housing 57 and the housing carries a threaded stud 58 which passes through a slot 59 in the ink pad carrier. A nut 60 secured to the stud detachably secures the ink pad to the carrier.

When the knob 34 and stem 32 is depressed, the depressible frame 26 connected thereto is depressed and through downward movement of the links 46 causes the ink pad carrier 50 to swing out away from engagement with the type wheels of the printing unit, to be described.

When the knob 34 is released, the spring 36 will cause the stem 32 to elevate with respect to the main frame 10, moving the depressible frame 26 upwardly to pivot the ink pad carrier 50 back to its normal horizontal position, as shown in Fig. 1, against the printing wheels. The structure comprising the main frame, the depressible frame and the operation of the ink pad carrier are conventional in present day hand stamps. The features comprising this invention will now be described.

The sides 28 of the depressible sub-frame 26, as best shown in Fig. 3, adjacent the bottom thereof are each provided with a horizontal channel or track 62 closed at the rear thereof as at 64 and open at the front thereof. Each of the sides 28 above the channel or track 62 is provided with a small opening 64. The track 62 is

adapted to receive the printing unit to be described and the openings 64 are adapted to receive the depressible extension pins on such printing unit for detachably locking the printing unit to the depressible sub-frame 26.

The printing unit, generally indicated at 66 is composed of a frame having side members 68 connected by a bottom cross-member 70. A shaft 72 extends between the upper portions of the side members 68 and carries the several rotatable spools 74 over which the several continuous type bands 76 pass and extend therefrom beneath the bottom cross-member 70, as is well understood. The side members 68 of the printing unit frame each has a rib 78 and a lateral lip 80 at the front thereof. Each of the side members 68 is provided with a small opening 82 above the rib 78. A spring actuated plunger generally indicated at 84 is adapted to be supported in the openings 82. The spring actuated plunger 84 comprises a cylindrical member 86 closed at one end and provided with a pin ex-

tention 88. The opposite end of the cylindrical member 86 slideably receives a plunger 90 which has a reduced pin extension 92 and a shoulder 93. A coil spring 94 in cylindrical member 86 acts against the plunger 90 to normally urge the plunger outwardly, as shown in Fig. 4. The plunger 90 has a head 95 which engages the flange end 96 of the cylindrical member 86 to limit the outward movement of the plunger. The opposite pin extensions 88 and 92 are retained in the openings 82 of the side members 68 of the printing frame. Said pin extensions are of such length that they will also extend into and be received in the openings 64 of the side members 28 of the depressible sub-frame 26.

Each of the side members 12 of the main frame 10 is provided with a small opening 98 (best seen in Fig. 1) so that when the depressible sub-frame 26 is depressed to the first depressible locking position, such as when the manually slideable cross-pin 38 engages the enlarged recess 33a, the openings 64 in the sides 28 of the depressible sub-frame 26 will be in alignment with the openings 98 of the main frame to permit insertion therethrough of a pin, not shown, for the purpose of urging the pin extensions 88 and 92 inwardly and out of engagement with the openings 64 to release the printing unit 66 from the depressible sub-frame 26 and to permit its removal therefrom. This may be readily accomplished by moving one of pin extensions 88 or 92 inwardly and slightly cocking the printing unit 66 so that the depressed pin extension remains out of the opening 64 and then following the same procedure with the opposite pin extension.

The printing unit 66, as best shown in Fig. 3, forms a separate unit which is readily attachable to and detachable from the depressible sub-frame 26 carried by the main base frame 10.

To attach the printing unit 66 to the depressible sub-frame 26, the depressible sub-frame is locked in its first depressed position as previously described. The ribs 78 of the printing unit frame are aligned with the guideways 62 of the depressible sub-frame 26 and the printing unit is pushed rearwardly. The pin extensions 88 and 92 will engage the openings 64 of the depressible sub-frame 26 when aligned therewith and will lock the printing unit to the depressible sub-frame 26, as best seen in Fig. 4. The ribs 78 provide the necessary support for the printing unit and the lips 80 serve to limit its rearward movement. The pin extensions 88 and 92 serve to detachably lock the printing unit to the depressible sub-frame. The printing unit 66 is thus positively locked in position for use, however, if it is desired to remove the printing unit for replacement or for the purpose of substituting another printing unit, the pin extensions 88 and 92 are pushed inwardly, as previously described, and the printing unit will be released for withdrawal from the depressible sub-frame 26.

While the invention has been described specifically in connection with a self-inking hand stamp, it will be understood that it is equally applicable to other types of hand stamps, as well as numbering machines.

It will be understood that various changes and modifications may be made from the foregoing without departing from the spirit and scope of the appended claims.

I claim:

1. A self-inking hand stamp comprising a base frame having a pair of side members each provided with an opening, a depressible frame member supported in said base frame, said depressible frame member having a pair of spaced legs each provided with a channel and each provided with an opening, a detachable printing unit having a pair of spaced side members each having a rib for sliding engagement with said channels, said printing unit carrying a depressible plunger having means engaging the openings in the spaced legs of the depressible frame member for detachably securing said printing unit to said depressible frame member, said depressible frame member when depressed having its openings aligned with

the openings of the side members of the base frame to permit engagement with the means on the depressible plunger to move said means out of engagement with the openings in the depressible frame.

5. A self-inking hand stamp comprising a base frame having a pair of side members each provided with an opening, a depressible frame member supported in said base frame, said depressible frame member having a pair of spaced legs each provided with a channel and each said leg provided with an opening, a detachable printing unit having a pair of spaced side members each having an opening, a spring biased plunger secured between said last mentioned side members with the opposite ends of said plunger received within said last mentioned openings, each said last mentioned side members having a rib for sliding engagement with said channels, said depressible frame member when depressed having its openings aligned with the openings of the side members of the base frame to permit manual engagement with the opposite ends of the plunger to permit withdrawal of the plunger ends from the openings in the depressible frame member.

3. A self-inking hand stamp comprising a base frame having a pair of side members each provided with an opening, a depressible frame member supported in said base frame, said depressible frame member having a pair of spaced legs each provided with an opening, a detachable printing unit having a pair of spaced side members each having an opening, the spaced legs of said depressible frame member and the spaced side members of the detachable printing unit having ribs and cooperating guideways whereby said ribs are slidably received in said guideways for securing said printing unit to said depressible frame, a spring biased plunger secured between the side members of the printing unit with the opposite ends of said plunger received within the openings of the depressible frame, said depressible frame member when depressed having its openings aligned with the openings of the side members of the base frame to permit manual engagement with the opposite ends of the plunger to permit withdrawal of the plunger ends from the openings in the depressible frame member.

4. A self-inking hand stamp comprising a base frame having a pair of spaced side members at least one of which is provided with an opening, a depressible frame member supported in said base frame, said depressible frame member having a pair of spaced legs at least one of which is provided with an opening, a detachable printing unit having a pair of spaced side members, said spaced legs of said depressible frame and said side members of said printing unit having ribs and cooperating channels whereby said ribs are slidably received in said channels for securing said printing unit to said depressible frame member, said printing unit carrying a depressible plunger having means engaging the opening in one of the spaced legs of the depressible frame member for detachably locking said printing unit to said depressible frame member, said depressible frame member when depressed having its opening aligned with the opening of the side member of the base frame to permit engagement with the means on the depressible plunger to move said means out of engagement with the opening in the depressible frame member.

5. A self-inking hand stamp comprising a base frame having a pair of side members at least one of which is provided with an opening, a depressible frame supported by said base frame, a printing unit carried by said depressible frame, said depressible frame and said printing unit each having a pair of spaced side members, at least one of each pair of side members having an opening, said side members of said printing unit having means cooperating with said side members of said depressible frame to support said printing unit within said depressible frame, a spring biased member carried by said printing unit and passing through the opening in the side mem-

ber of said printing unit and adapted to engage the opening in the spaced side member of said depressible frame to detachably lock said printing unit to said depressible frame member, said depressible frame when depressed having its opening alined with the opening of the side member of the base frame to permit engagement with the spring biased member to move same out of engagement with the opening in the depressible frame member.
